UNITED STATES PATENT OFFICE.

BENJAMIN LOMAX HARDY, OF MOBILE, ALABAMA.

ROTARY GASOLINE MOTOR.

Application filed June 23, 1924. Serial No. 721,759.

To all whom it may concern:

Be it known that I, BENJAMIN LOMAX HARDY, a citizen of the United States, residing at Mobile, in the county of Mobile 5 and State of Alabama, have invented certain new and useful Improvements in a Rotary Gasoline Motor, of which the following is a specification.

This invention relates to rotary gasoline 10 motors and it consists in the novel features hereinafter described and claimed.

An object of the invention is to provide a motor of the character stated which is of simple and durable structure having its 15 parts and features so assembled and arranged as to affect a preliminary compression of the gases or mixture and means for passing the fuel in compressed form into an explosion chamber in which a series 20 of pistons is mounted for rotation.

With this object in view the motor includes a shaft carrying a series of pistons and passing transversely through the explosion chamber and a compression cylinder 25 having a piston movably mounted thereon, means being provided for operatively connecting the shaft with the piston.

An abutment is connected with the piston and is adapted to move transversely 30 across the explosion chamber and is provided with openings through which the pistons may pass. The said abutment is further provided with ducts for passing the compressed gases from the compression 35 chamber into the explosion chamber. A spring pressed valve is provided at the intake which connects with the compression chamber and means are provided upon the shaft for opening the valve to permit the 40 gas to enter the compression chamber as the piston is moving upon its intake stroke.

In the accompanying drawings:—

Figure 1 is a top plan view of the motor with parts thereof in section.

Figure 2 is a similar view of the motor showing the piston at the end of its intake stroke.

Figure 3 is a side elevation of the motor with parts in section.

Figure 4 is a transverse sectional view through the explosion chamber of the motor.

Figure 5 is a transverse sectional view through the compression chamber of the motor.

The rotary gasoline motor comprises a

base 1 having a standard 2 mounted thereon and in which a shaft 3 is journaled for rotation. An explosion chamber 4 is mounted upon the base 1 and a shaft 5 passes 60 transversely through the explosion chamber and is provided at one end with a beveled pinion 6 which meshes with a beveled pinion 7 mounted upon the shaft 3. A compression chamber 8 is mounted 65 upon the base 1 and a gas conduit 9 communicates with one end portion thereof. A spring pressed valve 10 is arranged to control the passage way through the conduit 9 and the stem of the said valve projects 70 beyond the side of the conduit. A star wheel 11 is mounted upon the shaft 5 and is arranged so that its peripheral surface will wipe over the stem of the valve 10 as the shaft 5 is rotated. A disk 12 is 75 mounted upon the shaft 5 and is housed within the intermediate portion of the explosion chamber 4. A series of spaced pistons 13 are mounted upon the periphery of the disk 12 and are housed within the 80 outer portion of the explosion chamber 4. The explosion chamber 4 is provided with an exhaust port 14.

A piston 15 is slidably mounted in the compression chamber 8 and an abutment 16 is fixed to the inner face of the piston 15. The abutment 16 is provided at its side with a duct 17 adapted to establish, at certain intervals, communication between the compression chamber 8 and the explosion chamber 4. The abutment 16 is further provided at one edge with a recess 18 through which the pistons 13 may pass as the disk 12 rotates. A rod 19 is connected at one end with the piston 15 and passes through the end wall of the compression chamber 8. A cross head 20 is connected with the outer end of the rod 19 and rods 21 are pivotally connected at one end with the opposite ends of the cross head 20 and pivotally 95 connected at their other ends with a cross bar 22 which is pivotally and eccentrically connected with a disk 23 mounted upon the shaft 3. Any suitable means (not shown) may be provided for firing the charges of 100 gas in the explosion chamber and such means may be in the form of usual spark plugs.

The operation of the motor is as follows—

Assuming that the shaft 5 has been started 110 in rotation, the beveled pinions 6 and 7 rotate the disks 23 whereby the bars 21 are

moved longitudinally and the rod 19 and piston 15 are reciprocated. As the piston 15 moves toward the valve 10, the gases which have been received within the compression chamber 8 are compressed and when the ducts 17 move into register with the interior of the explosion chamber 4, the solid portion of the abutment 16 is disposed completely across the explosion chamber 4 and the said 10 gases are then exploded in the chamber 4 whereby they expand and operate against the end of one of the pistons 13 and augment the rotary movement of the shaft 5. After the explosion takes place, the valve 16 moves 15 from the position shown in Figure 1 of the drawing to the position shown in Figure 2, whereby one of the pistons 13 may move through the clearance space provided at the recess 18 and the piston 15 is retracted upon 20 its intake stroke whereby the gas is drawn in through the conduit 9 into the chamber 8.

As the shaft 5 rotates the pointed end portions of the stelliform wheel 11 engage the stem of the valve 10 whereby the said valve 25 is moved to an open position to permit the flow of the gas from the conduit 9 into the compression chamber 8. The points of the wheel 11 are so timed with relation to the movement of the piston 15 that the valve is 30 opened while the piston is moving upon its intake stroke and as the piston moves upon its compression stroke the point of the wheel 11 passes beyond the stem of the valve 10 whereby the said valve may close under the 35 influence of the impelling spring and consequently communication between the interior of the compression chamber 8 and the conduit 9 is interrupted and the gases compressed in the chamber 8 by the forward 40 movement of the piston 15 and when the end of the duct 17 comes into register with the interior of the explosion chamber 4, the said compressed gas is expelled from the compression chamber by the action of the piston 45 15 into the explosion chamber.

Having thus described the invention, what I claim is:—

1. A rotary motor including an explosive chamber, a shaft journaled transversely

therein, pistons operatively connected with 50 the shaft and housed within the explosive chamber, a compression chamber, a piston mounted for reciprocation in the compression chamber, means operatively connecting the piston with said shaft, a valve controlled 55 conduit for leading the fuel into the compression chamber, means carried by the shaft for operating the valve, a plate abutment carried by the last mentioned piston and adapted to move transversely across the explosion chamber and having a duct formed in one longitudinal edge adapted to transmit the gas from the compression chamber into the explosion chamber and provided with a recess through which the first mentioned pistons may pass.

2. A rotary motor including in combination, a base, a shaft journaled transversely of the base at one end thereof, an explosion chamber mounted at the other end of the base, a shaft journaled transversely through the explosion chamber and longitudinally of the base, gearing connecting the two shafts, a compression cylinder mounted longitudinally of the base between the first mentioned shaft and the explosion chamber, pistons operatively connected with the second shaft and housed within the explosion chamber, a second piston mounted for reciprocation in the compression cylinder, means operatively 75 connecting the second piston with the first shaft, a valve controlled conduit for leading the fuel into the compression cylinder, means carried by the second shaft for operating the valve, a plate abutment carried by the second 80 piston and adapted to move transversely across the explosion chamber and having a duct formed in one longitudinal edge extending from the piston and terminating at an intermediate point of the abutment and 85 adapted to transmit the gas from the compression cylinder into the explosion chamber, said abutment being further provided with a recess through which the first pistons may pass.

In testimony whereof I affix my signature,

BENJAMIN LOMAX HARDY.
